CORD-WINDING DEVICE

Gustaf Einar Lofgren, Riverside, Conn., assignor
to Electrolux Corporation, Dover, Del., a corporation of Delaware

Application January 16, 1941, Serial No. 374,635

3 Claims. (Cl. 15—246)

My invention relates to an improved electric cord-winding device which is especially adapted for use in connection with an enclosed bag type of vacuum cleaner.

In accordance with my invention, the cord-winding device includes a casing which may be secured to the main vacuum cleaner housing in place of the usual closure member at the exhaust end of the cleaner. This closure member is provided with an exhaust air opening to which a hose, vaporizer or the like may be connected and one of the objects of my invention is to construct the cord-winding device with a substantially airtight passageway therethrough which terminates in such an exhaust opening.

Another object of my invention is to provide a separable electrical connection between the cord-winding device and the vacuum cleaner such that, if for any reason it is desirable to remove the cord-winding device, the vacuum cleaner may be used with an ordinary electric cord.

Further objects and advantages of my invention will be apparent from the following description considered in connection with the accompanying drawings, which form part of this specification and of which:

Fig. 1 is a side view, partially broken away, of the cord reel in accordance with my invention secured to a vacuum cleaner;

Fig. 2 is an enlarged cross-sectional view of the cord reel and a portion of the cleaner illustrated in Fig. 1;

Fig. 3 is a side view, partially broken away, of the cord reel shown in the preceding figures;

Fig. 4 is a cross-sectional view on a reduced scale taken on the line 4—4 of Fig. 3;

Fig. 5 is a cross-sectional view on an enlarged scale taken on the line 5—5 of Fig. 2; and

Fig. 6 is a cross-sectional view taken on the line 6—6 of Fig. 5.

Referring to the drawings, reference character 10 designates generally the cord-winding device in accordance with my invention, while reference character 12 designates generally a known type of vacuum cleaner. Vacuum cleaner 12 includes an outer housing 14 made up of a central member 16 and a rear member 18. Suitably supported within the housing is an electric motor 20, on the armature shaft of which are mounted fan rotors 22. A dust bag 24 is disposed within the casing immediately ahead of the fan. The forward end of the casing is provided with a removable closure member 26 formed with an inlet opening 28, which opening communicates with the interior of the dust bag in well known man-

ner. Runners 30 serve to support the vacuum cleaner horizontally on any horizontal surface, such as a floor.

The rear member 18 of the vacuum cleaner 5 housing includes a transverse wall 32 provided with one or more openings 34, as is shown in Fig. 2, which openings serve for the flow therethrough of air discharged from the fan rotors 22. Member 18 is formed with an annular seat 10 36 which may receive an end cap or the like which is provided with an air exhaust opening to which may be secured a hose in the event it is desired to use the cleaner for blowing purposes. In accordance with my invention, such end cap is 15 removed and replaced by the cord-winding device 10.

As shown, this device includes an outer substantially cylindrical casing 38, one end of which is open and is dimensioned so as to closely fit 20 within the seat 36. The other end of the casing is formed as a transverse wall 40 in which is formed an exhaust air opening 42. Received within this opening is an annular channel member 44 to which is secured, as by riveting, a plurality of inwardly extending pins 46. The inner ends of these pins are secured to a plate member 48 and slidably supported on the pins is a ring member 50 across which extend a plurality of inclined louvers 52. A spring 54 is disposed 25 between plate 48 and member 50 and tends to force the member 50 to the right, as viewed in Fig. 2, so that the louvers 52 are disposed immediately within the exhaust opening in order that the air flowing therethrough may be deflected upwardly and away from the surface on which the vacuum cleaner is supported. However, if it is desired to connect a hose or the like to the exhaust opening, the member 50 may be 30 displaced inwardly by the end of the hose so as to permit the latter to extend within the opening.

An annular channel member 56 is secured within casing 38 and supports a transverse partition 58. For ease of assembly, plate 58 is made separate from the channel 56, but when assembled an airtight seal is maintained between them by means of the gasket 60 of rubber or other suitable material. Partition 58 is formed with a centrally located opening and the material of the 35 partition is drawn so as to provide annular rings 62 and 64.

A hollow body 66 is formed with a cylindrical portion 68 and a conical portion 70. One end of the cylindrical portion engages within ring 64 55 so as to form a substantially airtight seal there-

with, and consequently with the partition 58. The conical portion 70 extends outwardly to meet the outer housing 38 closely adjacent to the open end thereof, and is secured to the outer housing by means of a plurality of screws 72 which engage angles 74 welded to the inner side of the casing 38.

Rotatably mounted on the cylindrical portion 68 of the hollow body is a cord-winding reel 76 which includes radial flanges 78 and 80 between which a cord 91 may be wound. A spiral spring 84 has its inner ends secured to the stationary annular ring 62, while its outer end is secured to an ear 86 which is struck out from the flange 80. Additional ears 87 are likewise struck out from this flange and serve to limit the expansion of the spring 84 when it is unwound.

Secured to flange 78 by means of a plurality of screws 88 is a ring 90 of Bakelite, hard rubber or other suitable insulating material. This ring is formed with a pair of concentric grooves 92 and 94 within which are received slip rings 96. These slip rings are held in place within the grooves by means of screws 98 which engage threaded members 100 suitably secured as by welding to the backs of the slip rings.

At one point the flange 78 is formed with an offset portion 102, the outer surface of which bears directly against the insulating ring 90. A block of insulating material 104 is disposed within the offset, and binding screws 106 and 108 pass through this block and engage the slip rings 96 in the grooves 94 and 92, respectively. The bare ends 110 of the conductors contained within the cord 91 may be secured under the heads of the binding screws, whereby these conductors are connected to the respective slip rings. The end of the cord 91 is preferably secured to the reel by means of a clamp 112 so that the joints between the conductors 110 and the binding screws are relieved of all mechanical strain. A cap 114 of insulating material covers the heads of the binding screws 106 and 108 and is secured in place by means of a bolt 116.

The conical part 70 of the hollow member 66 is recessed, as is shown at 118, and an insulating block 120 is positioned within the recess. A bolt 122 engages another block of insulating material 124 which carries brushes 126 and 128 which are made of resilient material and positioned so as to have sliding contact with the slip rings in grooves 92 and 94, respectively. The brushes are secured to the block 124 by means of bolts 130, the inner ends of which engage bars 132 which extend outwardly beyond the insulating blocks 120 and 124. The outer ends of these bars are provided with binding screws 134 to which are connected conductors 136 which lead to a female plug 138 which is rigidly mounted on the upper side of the casing 38. The casing is also formed with an opening 140 through which the cord 91 passes.

Suitably mounted within the vacuum cleaner casing is an electric switch 142. As shown, this switch is mounted on a bracket 144 which is riveted to the transverse wall 32. The switch is provided with a button 146 which extends through the upper part of the vacuum cleaner casing and may be depressed to open and close the switch. The switch also carries a pair of prongs 148 which are disposed within an opening 150 formed in the transverse wall 32. These prongs are so positioned with respect to the seat 36 that when the cord-winding device is received in this seat, the plug 138 engages the prongs. 70

The cord-winding device 10 may be secured to the vacuum cleaner proper by means of knurled nuts 152 which engage bolts suitably secured to the vacuum cleaner housing and which pass through lugs or the like extending from the casing 38.

If desired, a filter member 154 may be disposed in the space between the transverse wall 32 and the conical member 70. This filter includes a ring 156 over which are stretched layers of filter cloth 158. Access may be had to this filter by removing the cord-winding device 10 from the vacuum cleaner.

The above-described device operates as follows:

When it is desired to connect the vacuum cleaner to an electrical outlet, the cord 91 is pulled outwardly through the opening 140 sufficiently to permit the male plug 160 on the outer end thereof to be inserted in a convenient outlet.

As the cord is pulled out, it causes the reel 76 to be rotated in a direction which winds up the spring 84. Consequently, the spring tends to rotate the reel in a direction to wind up the cord thereon. Hence, if the plug 160 is removed from the outlet, the reel will wind up the cord.

The current from the two conductors of the cord is transmitted through the binding screws 106 and 108 to the slip rings and thence through the brushes 126 and 128 to the screws 130. The current passes through the latter to the bars 132 and thence to the conductors 136 leading to the plug 138. From here the current passes to the prongs 148 and through the switch 142, assuming the switch to be closed, to the motor 20.

Rotation of the fan 22 causes air to be drawn into the dust bag 24 through the inlet opening 28. The air passes through the dust bag to the fan and is discharged therefrom through the motor 20 and passes through the opening 34 in the wall 32. From here it flows through the filter 154 and into the hollow member 66, from which it is discharged into the space within the casing 38 beyond the partition 58. From this space the air is discharged through the outlet 42, the louvers 52 directing it upwardly and away from the floor. It will be noted that the hollow member 66 and the partition 58 serve to seal the space which is occupied by the reel 76 from the air stream. Consequently, there is no possibility of air leakage through the opening 140 for the cord or around the connector plug 138. Consequently, all of the air discharged from the vacuum cleaner must pass through the opening 42. This is of importance when a hose or the like is connected to the opening in order that there shall be no loss in pressure of the air introduced into the hose.

If for any reason it would be desirable to remove the cord-winding device, this may be done by unscrewing the nuts 152 and pulling the device horizontally away from the cleaner. This withdraws the casing 138 from the seat 36 and disengages the plug 138 from the prongs 148. Even with the cord reel removed, the cleaner may still be operated if there is available an ordinary cord having a female plug of suitable size to engage the prongs 148.

If it is necessary to disassemble the cord reel for any reason, this may be done readily by removing the screws 72. Thereupon, the hollow member 66 and partition 58 may be withdrawn from the casing. In this connection, it will be noted that the flanges 78 and 80 are provided with notches 162 which may be aligned with the

brackets 14 in order to permit the reel to pass the brackets. The gasket 60 permits the partition 58 to be disengaged from the channel member 56.

While I have shown one more or less specific embodiment of my invention, it is to be understood that this has been done for purposes of illustration only and that the scope of my invention is not to be limited thereto, but is to be determined by the appended claims.

What I claim is:

1. In a cord-winding device, a substantially cylindrical casing having openings at opposite ends, one of said openings having a diameter substantially equal to that of the casing, a hollow body disposed within said casing and defining at least a portion of an airtight passage connecting said openings, said body having a cylindrical part of less diameter than said casing and a conical part extending therefrom to said casing adjacent to said one opening, means entirely within the casing and accessible through said one opening for removably securing said conical part to said casing, a transverse partition secured to the end of said cylindrical part remote from said conical part, means including a gasket providing a separable airtight seal between said partition and said casing, and a reel rotatably mounted on and concentric with said cylindrical part.

2. In a cord-winding device, a substantially cylindrical casing having openings at opposite ends, one of said openings having a diameter substantially equal to that of the casing, a hollow body secured within said casing and defining at

least a portion of an airtight passage connecting said openings, said body having a cylindrical part of less diameter than said casing and a conical part extending therefrom to said casing adjacent to said one opening, means for removably securing said conical part to the casing, a reel rotatably mounted on and concentric with said cylindrical part adjacent to said conical part, said reel including a radial flange, and electric transmission means including a brush member co-operating with a slip ring member, one of said members being mounted on said flange and the other member being mounted on said conical part.

3. In a cord-winding device for use with an electric vacuum cleaner having a housing formed with an exhaust air outlet and an electric push connector adjacent thereto, a casing formed with spaced openings, hollow structure defining at least a portion of an airtight passage connecting said openings, a reel within said casing concentric with and rotatably mounted on said structure, an electric cord windable upon said reel, means for removably securing said casing to said housing with said outlet communicating with one of said openings, an electric push connector fixed to said casing in a position such that it co-operates with the connector on said vacuum cleaner housing when said casing is secured to the housing, and means establishing an electrical connection between said cord and the connector on the casing.

GUSTAF EINAR LOFGREN.
